ASHTRAY

Ute Berger, 75 Wandersmannstrasse, Wiesbaden-Erbenheim, Germany

Filed Apr. 15, 1971, Ser. No. 134,529

Term of patent 14 years

U.S. Cl. D85—2 P Int. Cl. D27—03

FIG. 1

FIG. 2

FIG. 3

FIG. 4

FIG. 5

FIG. 1 is a top and front perspective view of an ashtray, showing one form of my new design;

FIG. 2 is a top plan view of the form shown in FIG. 1;

FIG. 3 is a left side elevational view of the form shown in FIG. 1;

FIG. 4 is a right side elevational view of the form shown in FIG. 1; and

FIG. 5 is a top and front perspective view of an ashtray, showing another form of my new design which is similar to FIG. 1, but with the tray being viewed from the opposite side and the key being inserted from the same direction as in FIG. 1.

I claim:

The ornamental design for an ashtray, as shown and described.
